(57) **CLAIM**

The ornamental design for a plug for an intraoral device, as shown and described.

DESCRIPTION

FIG. 1 is a front, upper, isometric view of a plug for an intraoral device of our new design;
FIG. 2 is a rear, lower, isometric view thereof;
FIG. 3 is a top plan view thereof;
FIG. 4 is a bottom plan view thereof;
FIG. 5 is a front view thereof;
FIG. 6 is a rear view thereof;
FIG. 7 is a left side view thereof; and,
FIG. 8 is a right side view thereof.

1 Claim, 4 Drawing Sheets
